C. C. MULDNER, Jr.

TURBINE TOY.

APPLICATION FILED MAY 28, 1917.

1,256,816.

Patented Feb. 19, 1918.

Inventor:

Carl C. Muldner, Jr.

Freddy Johnson.
Attorney.

UNITED STATES PATENT OFFICE.

CARL C. MULDNER, JR., OF MAPLEWOOD, MISSOURI.

TURBINE TOY.

1,256,816.

Specification of Letters Patent. Patented Feb. 19, 1918.

Application filed May 28, 1917. Serial No. 171,415.

To all whom it may concern:

Be it known that I, CARL C. MULDNER, Jr., a citizen of the United States, residing at Maplewood, in the county of St. Louis and 5 State of Missouri, have invented certain new and useful Improvements in Turbine Toys, of which the following is a specification.

My present invention relates to turbine toys, the same being an improvement of application bearing Serial No. 92,799, filed April 21, 1916, and has for its object to provide a turbine toy adapted to be driven by hot or cold air currents, such as a draft, and which consists of a minimum number of 10 parts, is neat in appearance, attractive when in operation, and capable of driving other smaller toys through the medium of a thread belt.

A further object of my invention is to 20 provide a comparatively cheap toy to take the place of the toy steam engine, toy electric motor, and similar power producing toys, thereby eliminating the damage of fire, accidents to children, explosions especially 25 in connection with the steam engine toy, and to provide an interesting toy for children that will exclude the expense and use of fuel which is necessary for the operation of toy steam engines and electric motor toys, 30 and still accomplish the same purpose as the more expensive power furnishing toys.

With the above and other objects in view, my present invention consists in certain new and novel arrangements and combination of 35 parts, as will be more fully described hereinafter and finally pointed out in the claims hereto appended.

Referring to the accompanying drawings forming a part of this specification wherein 40 like characters of reference denote similar parts throughout the several views—

Figure 1, is a end elevation of my improved toy turbine constructed in accordance with my invention, and shown as positioned in an open window.

Fig. 2, is a front elevation thereof.

Fig. 3, is a vertical sectional view of my improved toy turbine.

Fig. 4, is a plan view of the band which 50 is adapted to form the circular housing. This view shows the various ears, slotted openings, and supporting legs of the toy before the band is formed into its final circular shape.

Fig. 5, is a plan view of one of the cross 55 brace members.

Fig. 6, is a top plan view of the band after being rolled into circular form and secured in this position with the cross brace members fixed thereto.

In carrying out the aim of my present invention, I use a single piece of flat stock preferably in the form of a metallic band 1, of any suitable width and length, as clearly shown in Fig. 4. This band may be of any 60 other material than of metal, if found desirable.

The band 1 is provided at one end with the longitudinally extending, fastening devices, such as ears 2, and at its opposite 70 end with the openings 3, for the passage of the ears of fastening devices 2.

The band 1 is further provided with the integral supporting legs 4 and 5, having the enlarged foot portions 6 and 7, respectively. Each of these T-shaped supporting legs 4 and 5 is stamped from the body of the band 1, near the center portion thereof, when in flat formation, as clearly shown in 75 Fig. 4.

The band 1 is finally rolled to form a circular housing and which will be known hereinafter as a fan housing, having an open front and back to permit the passage of air currents or drafts therethrough. The 80 band 1 is fastened at its meeting edges, when formed into a circular housing, by means of the fastening devices or ears 2, passing through the openings 3, and clenched over the outer peripheral surface of the housing, 85 as clearly shown in Fig. 6. The fastening means is preferably positioned at the top of the housing, although it could be positioned at the bottom thereof, if found desirable, which would, of course, necessitate 90 stamping the supporting legs 4 and 5, from the band 1, near each end thereof, instead of near the center thereof, as is manifest.

The supporting legs 4 and 5, it will be observed, are bent downwardly from the 100 body of the circular housing preferably assuming a vertical position. These laterally disposed legs 4 and 5 have their foot portions 6 and 7 thereof, bent to an angle with relation to their respective legs and are 105 preferably adapted to extend outwardly from the legs 4 and 5 forming a substantial base for the fan housing, as clearly shown

in Fig. 2. The lowermost portion of the housing is also adapted to lie in a plane with the foot portions 6 and 7, of legs 4 and 5, respectively, so as to provide a more substantial base for the fan housing, as clearly shown in Fig. 2. This supporting means, it will be observed, will prevent any possible rolling of the fan housing and will permit the same to stand alone. It will thus be seen that the toy has three points of bearing upon any suitable support for holding the toy in an upright position.

To stiffen and brace the fan housing formed by the band 1 and to further provide a suitable support and bearings for a drive shaft, I provide the fan housing with a pair of cross-brace members 8. These cross-brace members 8 are each provided, at their ends, with the longitudinally extending, fastening devices or ears 9. These ears 9 are adapted to pass through the openings 10, in the band 1, as shown in Figs. 2 and 6, and adapted to be clenched to engage the peripheral surface of the fan housing. The cross-braces 8 are adapted to be vertically disposed within the fan housing, as clearly shown in Fig. 2, thereby providing suitable stiffening means for the housing as well as acting as a drive shaft supporting means.

A drive shaft 11 is journaled in the cross-braces 8 and rotatably supported thereby. A drop or two of solder 12, or its equivalent, is applied to the rear end of the shaft 11 to prevent sliding movement thereof in one direction only. The opposite end of the shaft 11 is provided with a suitable pulley 13, preferably a cone-shaped pulley, having a plurality of belt engaging grooves, such as 14, 15 and 16, of different diameters, for the purpose of changing the speed of the driven object. A suitable endless belt 17, preferably made from a heavy thread, is adapted to ride in the various grooves of the pulley 13, as is manifest. The endless belt 17 is adapted to ride, at its opposite end, over a suitable driven pulley 18, fixed to a shaft 19, carrying a suitable fan wheel 20, or other movable object of an auxiliary toy. This particular wind-mill toy, as illustrated, is only shown and described to serve as an illustration that the toy turbine is capable of driving or operating similar auxiliary toys.

It will be observed that the band 1 forming the fan housing, is provided with a pair of integral supporting ears 21 for the purpose of suspending the toy in front of an opening, through which a draft is adapted to pass, instead of resting the toy upon its supporting legs 4 and 5 and the bottom of the housing intermediate the supporting legs.

Figs. 1 and 2, of the drawings, illustrate the toy as standing on a window-sill 22, with the window-sash 23 open, and engaging the

uppermost peripheral surface of the fan housing for holding the housing from displacement upon the window-sill. The auxiliary toy may be positioned upon any suitable supporting device, such as a table, a floor, or the like.

It will be observed that owing to the fact that my turbine toy furnishes power from a drive propelled fan-wheel that it may be operated without expense, and that it will operate whenever placed over or in the path of a drive or air currents whether hot or cold. For instance, it may be operated in front of an open window or door, or in the open where there is a breeze, or it may be operated in front of a hot air register or upon a hot air register, or in front of a chimney flue, and, in fact, most any draft will propel the fan-wheel for producing power for driving other objects.

It will be readily understood that by using a suitable line shaft, two or more auxiliary toys may be operated through the medium of my turbine toy.

I am aware that various slight and minor details of construction may be resorted to without departing from the true spirit of my invention, hence reserve the right to make any such changes as may fall within the scope of the appended claims when fairly construed.

What I claim is:

1. A turbine toy comprising a flat metallic band rolled to form a circular housing having an open front and back, a clenchable fastening means for uniting the meeting ends of said circular housing, a pair of vertically disposed, opposed cross-braces spanning said housing, clenchable fastening means for uniting the ends of said cross-braces to said housing, a pair of laterally disposed supporting legs integral with the wall of said housing, a power shaft rotatably supported by means of said cross-braces, a drive pulley fixed to said shaft, a draft propelled power producing fan-wheel fixed to said shaft within said housing, and a belt driven by said pulley for operating auxiliary toys.

2. A turbine toy comprising a flat metallic band rolled to form a circular housing having an open front and back, clenchable fastening means for uniting the meeting ends of said circular housing, a pair of vertically disposed, opposed cross-braces spanning said housing, clenchable fastening means for uniting the ends of said cross-braces to said housing, a pair of laterally disposed supporting legs integral with the wall of said housing, a power shaft rotatably supported by means of said cross-braces, a drive pulley fixed to said shaft, a draft propelled power producing fan-wheel fixed to said shaft within said housing, a belt driven by said pulley for operating aux-

iliary toys, and a pair of supporting ears formed integral with said housing for hanging said housing in a suspended position in the path of a draft adapted to propel said fan-wheel.

5. A turbine toy comprising a flat metallic band rolled to form a circular housing, a pair of supporting legs stamped from the wall of said housing adapted to prevent rolling movement of said housing and support the same in an upright position, stiffening means for said housing, a power shaft rotatably supported within said housing, a cone pulley fixed to said shaft, a draft propelled power producing fan-wheel fixed to said shaft within said housing, and a pair of supporting ears stamped from the wall of said housing.

10. A turbine toy comprising a circular housing formed from a flat band having an open front and back, clenchable fastening means for uniting the free ends of said band

to form said circular housing, lateral supporting legs formed integral with said circular housing and depending therefrom and the lower extremities thereof adapted to lie in a plane with the lowermost peripheral point of said circular housing, a pair of vertically and oppositely disposed cross-braces spanning said circular housing within the front and rear edges thereof, clenchable fastening means for uniting the opposite ends of said cross-braces with the circular housing, a power shaft rotatably supported by said cross-braces within said circular housing, a draft propelled power producing fan fixed to said shaft adapted to drive said shaft when propelled by air currents, a cone pulley fixed to said shaft, and a drive belt for said pulley.

15. In testimony whereof, I have hereunto signed my name to the specification.

CARL C. MULDNER, JR.
